UNITED STATES PATENT OFFICE.

FRED A. LUNDAHL, OF MOLINE, ILLINOIS.

DESIGN FOR TOY TRUCK.

Application filed October 8, 1925. Serial No. 15,065. Term of patent 14 years.

To all whom it may concern:

Be it known that I, FRED A. LUNDAHL, a citizen of the United States, residing at Moline, in the county of Rock Island and State of Illinois, have invented a new, original, and ornamental Design for Toy Truck, of which the following is a specification, reference being made to the drawing forming a part thereof.

In the annexed drawing, Fig. 1 is a view in elevation of my new toy truck, the ladder being shown in dotted lines, and Fig. 2 shows a plan view thereof with the ladder in dotted lines and partly broken away.

I claim:

The ornamental design for toy truck as shown.

FRED A. LUNDAHL.
